4 Claims. (Cl. 197—177)

This invention relates to bookkeeping and like printing calculating machines and more particularly to mechanism therein for arresting the paper carriage in desired column positions comprising settable stops on the paper carriage cooperating with a frame stop which is brought out of operative position at the end of each machine operation against the action of a spring holding said frame stop in operative position, and a pawl for locking the frame stop in its in-operative position.

The primary object of the invention is to improve mechanism of this kind in such a manner that it is possible to print amounts registered in the balance accumulator of the machine separately in different paper carriage positions dependent on whether said amounts are positive or negative balances, and if desired to segregate these amounts simultaneously in different accumulators corresponding to their positive or negative character.

According to the present invention this result is achieved by making the pawl which locks the frame stop retractable by means of two different control members which are settable on the paper carriage and assigned to different carriage positions, the control member assigned to a position first reached by the paper carriage being operative or not in dependence on the sign of the amount indicated by the balance accumulator.

A constructional example of the mechanism according to the invention is illustrated in the accompanying drawings in which:

Figure 1 is a sectional view of a machine equipped with mechanism according to the invention,

Figs. 2 and 3 show details of the mechanism in different working positions,

Fig. 4 shows means for controlling the frame stop for arresting the paper carriage,

Fig. 5 is a plan view of the shaft carrying the frame stop,

Fig. 6 shows a detail of Fig. 1,

Fig. 7 shows a device for tensioning the paper carriage spring, and

Fig. 8 is a section on line 8—8 of Fig. 7.

The machine illustrated has an under frame 1 in which the paper carriage is slidably mounted in guides 3, 4. The paper carriage 2 is moved in the working direction by a tension spring not illustrated, which is attached to a flexible cord 10, Figs. 7 and 8. The flexible cord 10 is secured to the paper carriage 2 by means of a clip 11 thereon. The casing of the paper carriage spring

is arranged on an extension of a frame plate 11, not shown.

To tension the carriage spring there is provided another flexible cord 12 one end of which is attached to a cord pulley 13. The other end of the flexible cord 12 may be connected to the shaft of a motor which also drives the machine. A gear 14 is fast on the cord pulley 13, which gear 14 engages a rack 15 on the paper carriage. 5 When the motor is started its shaft drives the flexible cord 12, rotates the pulley 13 and gear 14, and thereby the paper carriage 2 is returned to its initial position and the carriage spring re-tensioned.

10 The paper carriage 2 has a base plate with a recess therein in which is mounted a frame 6. The frame 6 has side members extending in the longitudinal direction of the paper carriage and having slots therein for the reception of bars 7 which carry control members 8 serving to control the several functions of the machine. Said bars 7 also serve as carriage stops for arresting the paper carriage 2. The bars 7 cooperate with a frame stop 9 which is fixed on a shaft 10 rotatably mounted in bearings 12 on the plate 11. A spring 13 urges the shaft 10 constantly in clockwise direction, Figs. 1 to 4, whereby the frame stop 9 tends to assume the position shown in Figs. 1, 4 and 5 in which it cooperates with the bars 7 when the paper carriage 2 is drawn in its working direction, for example, by the carriage spring. When the paper carriage 2 is moved in the opposite direction, an oblique surface on the frame stop 9 comes into contact with the bars 7. 20 In this movement of the paper carriage, therefore, each bar 7 causes a counter-clockwise rotation of the shaft 10 as it moves past the frame stop 9. Immediately after passing a bar 7 the shaft 10 and frame stop 9 are restored to initial or locking position. The locking position of the frame stop 9 is determined in the mechanism illustrated by means of a locking member 14 which can rest against an abutment 15 on the plate 11. According to Fig. 5, the abutment 15 is resilient. 25 In order that the paper carriage 2 may not make too violent impact against the frame stop 9, the shaft 10 carrying this stop may be arranged with capacity for a slight longitudinal sliding movement against the action of a spring 16, the arrangement preferably being such that the spring 16 is weaker than the carriage spring so that each bar 7 will always determine an exact position of the paper carriage 2. The end stop for the longitudinal movement of the shaft 10 is 30 preferably resilient and may be provided with a

35

40

45

50

55

rubber cushion 17 as shown. Furthermore, the shaft 10 may have a projection which prevents engagement of the machine drive as long as the shaft 10 is not in its end position.

At the end of each machine operation the frame stop 9 must be briefly withdrawn in order to release the bar 7 which it previously engaged, and to allow the paper carriage 2 to move under the influence of the carriage spring into the next column position. For this purpose the following means are provided, see Fig. 4. The shaft 10 of the frame stop 9 has a toothed sector 18 attached thereto engaging corresponding teeth on a disk 19 which is rotatably mounted on a shaft 20 and carries a roller 21 operating as a crank pin. When the shaft 19 is rotated in clockwise direction the shaft 10 is rotated counterclockwise and the frame stop 9 retracted.

A shaft 22 is connected through link means 23, 24 and 25 to the main shaft 26 of the machine, Fig. 4, on which shaft 22 is mounted a disk 23 to which an operating member 26 is slidably connected by means of a pin and slot joint 24, 25, which operating member 26 is acted upon by a tension spring 27. The main shaft 26 can be oscillated manually or by an electric motor not shown. At each machine operation the shaft 22 receives an oscillating movement in the first part of which the shaft 22 rocks in clockwise direction. In this rocking movement of the shaft 22 the operating member 26 slides along the roller 21 of the disk 19 and finally away therefrom, so that it can move to the right relatively to the disk 23, under the action of the spring 27. When the shaft 22 performs its return stroke in the second part of the machine operation, the operating member 26 engages below the roller 21 and effects a clockwise rotation of the disk 19 and resulting retraction of the frame stop 9. During the upward movement of the roller 21 under the action of the operating member 26, the roller, after the frame stop 9 has been sufficiently retracted, moves away from the upper surface of the operating member 26. This releases the spring 13, causing the shaft 10 again to rock in clockwise direction and restore the frame stop 9 to its working position before the next bar 7 comes into its range of action. Since the disk 19 engages the toothed sector 18 and the shaft 10, the disk 19 is also returned by the spring 13 to the position shown in Fig. 4, and thereby the roller 21 presses the operating member back to its initial position against the action of spring 27.

In order to prevent return movement of the frame stop 9 at the end of a machine operation, there is provided a crank 28, the pin 29 of which can be brought to bear against the operating member 26 in such a manner that movement of the latter by the spring 27 cannot take place. When the crank 28 is brought into the position shown in Fig. 4, there is consequently no forcing back of the frame stop 9 and the paper carriage will not effect a movement at the end of the machine operation, but will remain in its previous position.

The locking member 14 on the shaft 10 cooperates with a pawl 30 fixed on a shaft 41, the arrangement being such that the pawl 30 will drop into its working position behind the locking member 14 raised during the retraction of the frame stop 9, and will thus prevent restoration of the frame stop 9 to its locking position under the action of the spring 13. The pawl 30 may be brought into operative position by a key 32 the stem of which acts on a bell-crank 33

to the lower arm of which a link 34 is jointed. The other end of this link 34 is jointed to a lever 35 pivoted at 36 and acted upon by a tension spring 43 urging it always in anti-clockwise direction. The upper arm of the lever 35 is jointed at 37 to a locking lever 38 acted upon by a spring 39, which lever 38 bears against a fixed pin 40. The end of the upper arm of the lever 35 has a shouldered notch 41 cooperating with a pin 42 arranged on a lever 44 fixed to the shaft 34 and this pin serves as a pivot for a locking pawl 45 which is connected by a tension spring 46 with the upper arm of the lever 35. The lever 44 is acted upon by a spring 48. The end of the spring 46 is attached to the lever 35 by means of a pin 47 which also acts as a stop for the movement of the pawl 45. In its working position the pawl 45 engages behind a square pin 48 on the locking lever 38, see Figs. 2 and 3.

20 The pawl 30 carries a pin 49 operating as a crank pin and cooperating with a lever 51 pivoted on a fixed pin 50. This lever 51 is connected by a link 52 with a lever 53 pivoted at 54 and which can be actuated by means of a control member 8 on the bar of the paper carriage 2. The shaft 31 carrying the pawl 30 also has mounted thereon a crank 55 with a crank pin 56 cooperating with a link 57 jointed to a bell-crank 58 mounted on a fixed pivot. The bell-crank 58 is connected by a link 59 with a lever 60 also pivoted at 54 and which can be actuated by a control member 8 on the paper carriage 2. The jointing of the link 57 to the bell-crank 58 is such that the free end of the link 57 can move to and fro by a small amount in a plane at right angles to the plane of the paper in Fig. 1, the amount of movement being longer than the length of the pin 56 of the crank 55. By rocking the link 57 it is therefore possible to bring a recess 64 in the link into or out of engagement with the pin 56. The rocking of the link 57 is effected by the lever 61 mounted on the shaft 62 which can be rotated, through connections not shown, either by hand or automatically in dependence upon 45 a change of sign in the amount indicated by the balance accumulator. To actuate the shaft 62 in accordance with change of sign of the balance accumulator contents, there may be used the means shown, for example, in U. S. Patent No. 1,046,552, which patent describes a machine employing mechanism for actuating an indicator of the sign of the accumulator content.

The control members 8 are so arranged on the paper carriage that the control member 8 acting upon lever 60 is operative in the paper carriage position reached by the carriage prior to the position in which the second control member 8 acts upon the lever 53.

60 The mode of operation of the described mechanism is as follows:

In normal operation of the printing calculating machine, in each machine operation the disk 23 is rocked causing the shaft 22 carrying the operating member 26 to effect an oscillating movement of the disk 19 and consequently a retraction of the frame stop 9 whereby the bar 7 previously held by the frame stop 9 is released and the paper carriage 2 caused to effect a movement until the frame stop, under the action 70 of the spring 13, becomes operative to engage the next bar 7 of the paper carriage. If the paper carriage is to effect a movement greater than that of the next bar, then the pawl 30 is brought into operative position by depressing the key 32. Upon depression of this key the arm

38 is rotated clockwise about pivot 36 and its shouldered recess 41 releases the pin 42 of lever 44. The lever 44 then moves clockwise under the pull of spring 63 and brings the pawl 38 mounted on the same shaft 31 into engagement with the locking member 14 fixed on the shaft 10 of the frame stop 9, see Fig. 2. Simultaneously the locking pawl 45 is released by the pin 47. During the movement of the lever 44 the locking pawl therefore moves downwards and engages behind the square pin 48 of the locking lever 38. The lever 38, during the rocking of the lever 35, slides to the right of the fixed pin 46 and snaps behind the same, see Fig. 2, thus locking the parts shifted by the key 32, in their new position. Fig. 2 shows the positions of the parts under depression of key 32.

In the ensuing machine operation, the frame stop 9 is retracted in the manner above described, in the course of which the rocking member 14 fixed on the shaft 10, also effects a rocking movement and forces the pawl 38 backwards against spring 63 until the pawl 38 can snap behind the locking member 14, see Fig. 3. The pawl 38 in this position prevents the frame stop 9 from returning to operative position under action of the spring 13. Consequently the paper carriage 2 moves under the action of this spring until the frame stop 9, by return movement of the pawl 38, is capable of again becoming operative to stop the paper carriage 2 at the next bar 7.

In the course of the paper carriage movement the control member 8 on the bar 7 actuates the lever 60 and draws the link 51 to the right, Fig. 1. If the contents of the balance accumulator has a certain sign, for example positive, the link 51 has its recess 64 in engagement with the pin 56 of crank 55, whereby upon actuation of the link 51 the pawl 38 is rocked out of its locking position. Under the action of the spring 13 the frame stop 9 would then assume its operative position and would arrest the carriage 2. If, however, the contents of the balance accumulator does not have the determined sign, for example if it is negative, then the link 51 is operated by the lever 61 on the shaft 62 in such a manner that its recess 64 is out of engagement with the pin 56 of crank 55. Actuation of the link 51 thus does not affect the pawl 38 in its locking position and the paper carriage 2 continues its travel notwithstanding the operation of the link 51.

On further movement of the paper carriage the second control member 8 acts upon the lever 53 and operates the lever 51 through the link 52. This lever presses against the pin 48 on the pawl 38 and thereby rocks the pawl against the action of spring 63 out of its locking position. This releases the locking member 14 whereby the frame stop 9 moves into position under the action of spring 13 to arrest the paper carriage.

On return of the pawl 38 into the position shown in Fig. 1 the lever 44 rocks upwardly. The square pin 48 of the pawl 45 then raises the locking lever 38 so that it is carried above the fixed pin 46. Since the notch in the locking lever 38 is no longer operative, the lever 38 is returned under the action of spring 43 into the position shown in Fig. 1.

In consequence the shouldered notch 41 of the lever 35 again lies below the pin 42, and the locking pawl 45 is forced back by the pin 47 and released from the square pin 48 of the locking lever 38. At the end of the described operation all

the parts of the mechanism are back in the position shown in Fig. 1.

The mechanism according to this invention makes it possible to cause the paper carriage of a printing calculating machine, by merely pressing the key, to jump through any desired number of column positions and to stop in one or the other of two predetermined carriage positions, in dependence upon the character, positive or negative, of the amount registered in the accumulator.

The present application is a division of my co-pending application Serial No. 39,065, filed September 3, 1935, now Patent No. 2,258,090, issued October 7, 1941.

I claim as my invention:

1. In a bookkeeping machine the combination of a machine frame, a paper carriage slidably arranged on the machine frame, means for moving the paper carriage in its normal direction, stop members arranged on the paper carriage, a stop shiftably arranged on the machine frame for cooperating with the stop members to stop the paper carriage in any column position, yielding means for holding the stop in its operative position, an oscillating main shaft, actuating means connected with the main shaft for bringing the stop during the last period of each oscillating movement of the main shaft to an inoperative position, a latch for locking the stop in its inoperative position, two means independent of each other for bringing the latch to its non-locking position, a member settable into two different positions, two control members arranged on the paper carriage in different column positions, each of the control members coacting with one of the said two means, and coupling means between the latch and that one of the two means which coacts with the control member which is arranged in the first of said column positions, said coupling means being connected with the settable member for being made effective or ineffective in dependence on the position of the settable member.

2. In a bookkeeping machine the combination of a machine frame, a paper carriage slidably arranged on the machine frame, means for moving the paper carriage in its normal direction, stop members arranged on the paper carriage, a stop shiftably arranged on the machine frame for cooperating with the stop members to stop the paper carriage in any column position, yielding means for holding the stop in its operative position, an oscillating main shaft, actuating means connected with the main shaft for bringing the stop during the last period of each oscillating movement of the main shaft to its inoperative position, a latch for locking the stop in its inoperative position, two means independent of each other for bringing the latch to its non-locking position, a member settable into two different positions, a rod for bringing the latch into its non-locking position, the rod being connected on the one end with the one of the two settable means and guided on the other end by the said settable member and being connected with or disengaged from the crank in dependence upon the position of the settable member, a lever connected with the other of the two settable means for bringing the latch into its non-locking position, controllable means for holding the latch in its non-locking position against the action of the spring, and two control members arranged on the paper carriage in different column positions, each of the control members acting upon

55

50

40

35

20

15

10

5

one of the said two settable means, that control member, which acts upon the settable means connected with the rod, being arranged on the paper carriage in the first of said column positions.

3. In a bookkeeping machine the combination of a machine frame, a paper carriage slidably arranged on the machine frame, means for moving the paper carriage in its normal direction, stop members arranged on the paper carriage, a stop shiftably arranged on the machine frame for cooperating with the stop members to stop the paper carriage in any column position, yielding means for holding the stop in its operative position, an oscillating main shaft, actuating means connected with the main shaft for bringing the stop during the last period of each oscillating movement of the main shaft to its inoperative position, a latch for locking the stop in its inoperative position, a spring for bringing the latch to its locking position, a crank connected with the latch, two settable means, a member settable to two different positions, a rod for bringing the latch into its non-locking position, the rod being connected on the one end with the one of the two settable means and guided on the other end by the said settable member and being connected with or disengaged from the crank in dependence upon the position of the settable member, a lever connected with the other of the two settable means for bringing the latch into its non-locking position, controllable means for holding the latch in its non-locking position against the action of the spring, two control members arranged on the paper carriage in different column positions, each of the control members acting upon one of the said two settable means, that control member which acts upon the settable means connected with the rod being arranged on the paper carriage in the first of said

column positions, and a key for setting the controllable means to their ineffective position.

4. In a bookkeeping machine the combination of a machine frame, a paper carriage slidably arranged on the machine frame, means for moving the paper carriage in its normal direction, stop members arranged on the paper carriage, a stop shiftably arranged on the machine frame for cooperating with the stop members to stop the paper carriage in any column position, an oscillating main shaft, actuating means connected with the main shaft for bringing the stop during the last period of each oscillating movement of the main shaft to an inoperative position, a latch for locking the stop in its inoperative position, a spring for bringing the latch to its locking position, a crank connected with the latch, two settable means, a member settable to two different positions, a rod for bringing the latch into its non-locking position, the rod being connected on the one end with the one of the two settable means and guided on the other end by the said settable member and being connected with or disengaged from the crank in dependence upon the position of the settable member, a lever connected with the other of the two settable means for bringing the latch into its non-locking position, controllable means for holding the latch in its non-locking position against the action of the spring, and two control members arranged on the paper carriage in different column positions, each of the control members acting upon one of the said two settable means, that control member which acts upon the settable means connected with the rod, being arranged on the paper carriage in the first of said column positions.

HEINRICH KONRAD FRIEDRICH EWALD.
